UNITED STATES PATENT OFFICE.

EDWARD S. HARTMAN, OF ALLEGHENY, PENNSYLVANIA.

PLOW-STANDARD CAP.

SPECIFICATION forming part of Letters Patent No. 398,831, dated March 5, 1889.

Application filed December 14, 1888. Serial No. 293,540. (No model.)

To all whom it may concern:

Be it known that I, EDWARD S. HARTMAN, a citizen of the United States of America, residing at Allegheny, in the county of Allegheny and State of Pennsylvania, have invented certain new and useful Improvements in Plow-Standard Caps, of which the following is a specification, reference being had therein to the accompanying drawings.

10 My invention relates to plows; and the objects of my improvement are to provide a light, strong, durable, inexpensive, and rapidly-produced cap of suitably-bent sheet metal to unite the standard to the beam of a plow. I

15 accomplish these objects by the construction illustrated in the accompanying drawings, in which—

Figure 1 is a side view of a portion of a plow-beam and standard united by a standard-cap constructed in accordance with my invention. Fig. 2 is a longitudinal vertical section of the same. Fig. 3 is a transverse section of the same. Fig. 4 is a perspective view of the standard-cap turned upside down. Fig. 5 is a 25 top view of a sheet-metal blank from which the improved standard-cap is produced.

Heretofore the caps of plow-standards have generally been made of cast-iron, lacking in tensile strength, although comparatively heavy and expensive to carry by mail or express, these modes of transportation being generally used by farmers when breakage occurs during very busy seasons. The purpose of my invention is to remove these objectionable features.

In the drawings an ordinary plow-beam is represented at A and its standard at B. These parts are securely united by means of the standard-cap D and bolts c, passing 40 through vertical perforations d in the ends of said cap and through the beam, with nuts c² bearing upon said beam. A bolt, e, passes also horizontally through perforations d² in the sides of said cap and through the upper end 45 of the standard. The cap D consists of sheet metal—preferably Bessemer steel—suitably bent, folded, and twisted to impart thereto the strength required of said cap to with-

stand the strain produced upon it by the beam and the standard. 50

To produce a standard-cap of this construction a sheet-metal blank of suitable thickness (approximately one-eighth of an inch) is cut or stamped in the form shown in Fig. 5, having two side lugs to form the cheeks d³ 55 of the cap. Centrally in said blank a mortise, d⁴, is cut in the form of a parallelogram corresponding with the size of the standard it is to receive, and a perforation, d⁵, is also made in each side lug or cheek, d³, for the reception of the standard-retaining bolt e. The blank is then placed in a press having a mandrel that enters the mortise d⁴ and retains it in proper position upon said press. The two long edges of the blanks are then bent up 60 against a templet on the lines shown dotted at f in Fig. 5. The templet is then removed and the turned-up edges adjacent to the two ends are forced down and folded at d⁶ upon the axial or main portion of the blank; but, as 65 the central portion or mortise, d⁴, still contains the mandrel, the cheeks d³ remain standing against it at an angle of ninety degrees to the body of the blank, and as a short twist is formed on the front and rear ends of the 70 blank where they join at d⁶ the flat folded portion d⁷, said twisted portion of the cheeks 75 constitutes supports for the front and rear edges of the standard if its upper end should happen to be below the under surface of the 80 edge of the mortise d⁴, either on account of carelessness in uniting the parts, or on account of wear or looseness of the transverse bolt in the bolt-holes d⁸ of the cheeks. 85

The cheeks of the cap are shown inclined 85 rearwardly in the drawings to correspond with the form preferred for the standard; but if the upper end of the standard is made to stand vertically the angle given to the cheeks of the cap would also be vertical. 90

Having now fully described my invention, I claim—

1. A plow-standard cap consisting of sheet metal having its long edges bent, the two ends of said bent edges folded upon the body 95 thereof, and projecting cheeks between said

two ends, the inner end of said cheeks being twisted, substantially as and for the purpose described.

2. The combination of a plow-beam and a plow-standard with a standard-cap consisting of a sheet-metal blank having its two longest edges provided with lugs and said lugs bent and twisted to embrace the plow-

standard, substantially as and for the purpose described. 10

In testimony whereof I affix my signature in presence of two witnesses.

EDWARD S. HARTMAN.
